Georges Kocens, 8462 Sunset Blvd., Los Angeles, Calif.
Filed July 24, 1957, Ser. No. 47,061

Term of patent 3½ years

(Cl. D58—2)

FIG. 4.

The container shown in broken lines is for illustration only.

I claim:

The ornamental design for a container insert for a cosmetic package, substantially as shown and described.
